CLAIM

The ornamental design for a bone plate as shown and described.

DESCRIPTION

FIG. 1 is a front, top, left perspective view of a bone plate according to our design;

FIG. 2 is another front, top, left perspective view thereof;

FIG. 3 is a bottom plan view thereof; and,

FIG. 4 is a right side elevation view thereof.

The broken line portion of the figure drawings is included to show unclaimed subject matter only for the purpose of illustrating environment and forms no part of the claimed design.

1 Claim, 3 Drawing Sheets
